UNITED STATES PATENT OFFICE

CARL HORIX, OF CHICAGO, ILLINOIS

BELT BUCKLE

Application filed November 8, 1926. Serial No. 146,916.

This invention relates to a buckle or holding device for securing together the opposite ends of a belt, and has for one of its objects the provision of a belt holding device which shall be neat and attractive in appearance, convenient to manipulate, reliable in operation and which will permit yielding expansion of the belt.

Further objects will appear from the following description.

The arrangement is exemplified in the combination and arrangement of parts shown in the accompanying drawing and described in the following specification, and it is more particularly pointed out in the appended claims.

In the drawing—

Fig. 1 is a front elevation of a belt buckle embodying one form of the present invention;

Fig. 2 is a section on line 2—2 of Fig. 1;

Fig. 3 is a section on line 3—3 of Fig. 1 on an enlarged scale;

Fig. 4 is a rear view of the buckle shown in Figs. 1, 2 and 3; and

Fig. 5 is a section on line 5—5 of Fig. 3.

To many persons the wearing of a belt is more or less of a discomfort for the reason that the belt must be fairly tight to be effective in supporting the trousers of the wearer and since a leather strap is practically unyielding the ordinary belt does not provide for the expansion and contraction of the waist-line which otherwise occurs in the activities of the wearer and which are essential to comfort and desirable for health. The present invention provides means for permitting considerable expansion and contraction of the body while maintaining the belt sufficiently tight at all times to properly operate. The necessary elasticity is provided in the buckle itself so that there is no necessity for a special strap or belt member and the appearance of the buckle is the same as the ordinary buckle.

Referring to the drawing, the numeral 10 designates a buckle plate which is bent backwardly at its top and bottom edges to provide flanges 11, shown best in Fig. 3. The rear edge of each flange 11 is rolled to provide a

tube 12, the outer edge of the tube being in registration with the outer edge of the plate 10, while the front side of the tube is spaced backwardly from the rear face of the plate to provide clearance between the plate and tube of sufficient width to admit the entrance of the belt between the buckle plate and the front sides of the tubes, as shown in Fig. 3. The tubes 12 are preferably flattened so that they have their greatest dimension in the direction parallel with the plate 10. An inner tube 13 is disposed within each of the tubes 12 and has a telescoping movement within the outer tube. The outer ends of the tubes 13 are shaped to form eyes 14 through which a pin 15 extends. A loop 16 is provided with a sleeve 17 which surrounds the portion of the pin 15 between the eyes 14. One end of a belt 18 is attached to the loop 16, the belt preferably being detachably connected to the loop 16 by means of snap fasteners 19. The usual leather loop 20 may be provided for receiving the free end 21 of the belt 18. The inner tubes 13 are resiliently held in retracted position within the outer tubes 12 by means of coil springs 22. While I have shown two circular coil springs in each tube, it will be apparent that any number or shape of spring desired may be employed. One end of each spring is attached to the portion of the rod 15 which extends through the eye 14 of the tube 13. The other end of each spring is attached to a sleeve 23 which surrounds a pin 24 extending through the outer tube 12 near the end thereof. The sleeve 23 is employed to assist in assembling the parts. The springs are first placed in the inner tubes 13 and the rod 15 threaded through the loops at the ends of the springs. The free ends of the springs are then attached to the sleeves 23 prior to insertion of the tubes 13 into the tubes 12. A wire or cord is then secured to the sleeve 23 and passed through an opening 25 in the portion 26 of the plate 10 which closes the end of the tube 12. By drawing on the cord the sleeve 23 is pulled into position to register with the openings for receiving the pin 24. The sleeve holds the loops in the ends of the springs in registration for the insertion of the pin 24.

Ears 27 are struck from the sides of the tubes 12 and bent backwardly to receive a pivot pin 28 upon which a buckle tongue or plate 29 is pivotally supported. The plate 29 is looped about the pivot 28 and is provided with a lever portion 30 which extends radially from the pivot 28 at an angle less than a right angle. The tongue 29 has a radial length slightly greater than the distance between the pin 28 and the rear face of the belt 18 when the belt is in position between the plate 10 and the tubes 12. This will prevent the tongue from swinging past the dead-center formed by the pivot pin 28 under the tension of the belt 18. The tongue 29 will always be inclined at the side of the pin 28 toward the loose end of the belt so that tension on the belt tends to tighten the grip of the tongue against the rear face of the belt. The lever 30 will ordinarily be spaced slightly in the rear of the rear face of the belt but will strike the rear face of the belt before the tongue passes its dead-center position and will then form a supplemental holder to augment the action of the tongue 29. It will be apparent that expansion of the belt will be permitted by the resiliency of the springs 22 which permit the tubes 13 to be drawn outwardly to accommodate the belt to expansion of the waist-line of the wearer. The springs 22 will always maintain a tension on the belt sufficient to take up any contraction in the waist-line and maintain a snug fit of the belt.

The only parts of the buckle which are visible when the belt is in place is the front face of the buckle plate 10. The expansion parts are entirely concealed by the loose end of the belt so that the buckle has exactly the same appearance as the ordinary belt buckle. The tongue 29 will grasp the belt at any point of adjustment and securely hold it against any force tending to withdraw the belt from the buckle. The greater the force exerted, the tighter will be the grip of the tongue on the belt. To release the belt it is only necessary to move the loose end through the buckle plate a slight distance in the direction of inclination of the tongue 29. This will release the tongue from engagement with the rear face of the belt and permit the belt to slide freely from the buckle. The buckle may be applied to the ordinary form of belt which is detachably secured to the buckle so that if the belt becomes worn it may be discarded and the buckle applied to a new belt.

I claim:—

1. A belt buckle comprising a buckle plate, housing members secured to opposite edges of said buckle plate and disposed in the rear of said buckle plate in spaced relation thereto, springs disposed in said housing members and connected therewith, means for securing

one end of a belt to said springs to provide a yielding connection of said end with said buckle plate, and pivoted gripping means on said plate for adjustably securing the other end of said belt to said buckle plate.

2. A belt buckle comprising a buckle plate having flanges extending rearwardly from opposite edges thereof and spaced apart to receive a belt therebetween, housing members fixedly supported by said flanges and extending inwardly toward each other in spaced relation to the rear face of said buckle plate, resilient means disposed in said housing members for attachment to one end of a belt, and means secured to said buckle plate for clamping the other end of said belt against the rear face thereof.

3. A belt buckle comprising a plate having opposite edges thereof bent to form tubular housings, springs disposed in said housings, means for attaching one end of a belt to said springs, ears struck from said plate to provide pivot supports, a pivot rod connecting said ears, a tongue pivotally mounted on said rod and bridging the space between said housings to grip the other end of said belt disposed at the rear of said plate, and an arm secured to said tongue to limit the movement thereof.

4. A belt buckle comprising a plate, housings fixed to said plate and rearwardly spaced therefrom adjacent opposite edges thereof to provide passageways for opposite edges of a belt between said housings and plate, a fastener for holding one end of said belt against movement in said passageways, springs disposed in said housings, and means other than said holding means for attaching the other end of said belt to said springs.

5. A belt buckle comprising a plate, springs supported on said plate and rearwardly spaced therefrom adjacent opposite edges thereof to provide clearance for the edges of a belt between said plate and springs, the springs at opposite edges of said plate being spaced from each other, means for connecting said springs to one end of said belt, and a fastening device for the other end of said belt disposed between said springs, said springs and fastening device being mounted on said plate independently of each other.

6. A belt buckle comprising a plate, housings fixedly mounted on said plate adjacent opposite edges thereof and spaced rearwardly therefrom to provide clearance for opposite edges of a belt between said plate and housings, springs disposed in said housings, means for attaching one end of a belt to said springs, and a fastening device for holding the other end of said belt from movement in one direction through said clearance space.

7. A belt buckle comprising a plate, housings fixedly mounted on said plate adjacent opposite edges thereof and spaced rearwardly therefrom to provide clearance for op-

posite edges of a belt between said plate and housings, springs disposed in said housings, means for attaching one end of a belt to said springs, a fastening device pivotally mounted on said housings and having a tongue projecting toward said plate between said housings for engaging the other end of said belt when disposed in the space between said plate and housings, said tongue being of sufficient length to engage said belt when said tongue is disposed obliquely to the surface of said belt, and an operating lever connected with said tongue and arranged to engage said belt to prevent said tongue from moving past a position normal to the surface of said belt.

8. A belt buckle comprising a plate having rearwardly extending opposite sides terminating in spring retainers which extend inwardly toward each other and in spaced relation to the rear face of said plate to form an unobstructed passage throughout the length of the buckle to permit the insertion of a belt through the buckle between said spring retainers and the rear face of said plate from one end thereof to the other, and means for connecting the opposite ends of said belt to said buckle.

9. A belt buckle comprising a plate having rearwardly extending opposite sides terminating in spring housings which extend inwardly toward each other and in spaced relation to the rear face of said plate to permit the insertion of a belt through the buckle between said housings and the rear face of said plate, a belt gripping device pivoted on said plate between said housings for gripping one end of said belt, and means for attaching the other end of said belt to said buckle.

40 10. A belt buckle comprising a plate having rearwardly extending opposite sides terminating in spring housings extending inwardly toward each other and in spaced relation to the rear face of the plate to permit the insertion of a belt through the buckle between said housings and the rear face of the plate, a pivoted rod carried by said plate and bridging the space between said housings, a tongue pivotally mounted on said rod to grip one end of said belt inserted between the housings and the rear face of the plate, an arm secured to said tongue to limit the pivotal movement thereof, and means for attaching the other end of said belt to said buckle.

55 11. A belt buckle comprising a plate having rearwardly extending opposite sides terminating in spring retainers which extend inwardly toward each other and in spaced relation to the rear face of said plate to provide a space for the insertion of a belt through the buckle having a width substantially equal to the width of the buckle, and springs substantially enclosed within said retainers to be 60 yieldingly connected to one end of said belt

and means for adjustably connecting the other end of said belt with said buckle.

12. A belt buckle comprising a plate having rearwardly extending opposite sides terminating in spring retainers which extend inwardly toward each other and in spaced relation to the rear face of said plate to provide a space for the insertion of a belt through the buckle having a width substantially equal to the width of the buckle, springs substantially enclosed within said retainers adapted to be yieldingly connected to one end of said belt and a belt gripping device on said plate pivoted between said retainers for gripping the other end of said belt.

70 13. In a belt to be worn about the waist, the combination of a buckle therefor comprising a plate having a width of substantially that of the belt and having rearwardly extending opposite sides terminating in spring housings which extend inwardly toward each other and in spaced relation to the rear face of said plate to permit the insertion of a belt through the buckle between said housings and the rear face of said plate, said rearwardly extending opposite sides of said plate and said housing defining a belt receiving space behind the plate of a dimension of substantially the width and thickness of the belt, springs in said retainers adapted to be yieldingly connected to one end of said belt, and a belt gripping device on said plate between said housings for gripping the other end of said belt.

75 80 85 90 95 100 In testimony whereof I have signed my name to this specification on this 6th day of November, A. D. 1926.
